(57) **CLAIM**

The ornamental design for a display screen with graphical user interface, as shown and described.

DESCRIPTION

FIG. 1 is a front view of a display screen or portion thereof with graphical user interface showing our new design; FIG. 2 is a front view of a second embodiment of FIG. 1; and,

FIG. 3 is a front view thereof, shown in an alternate environment.

The outer broken line perimeter illustrates a display screen or portion thereof and forms no part of the claimed design. The remaining broken lines show portions of the graphical user interface and form no part of the claimed design. The different shades of gray illustrate contrasting appearances.
